J. M. GANDY, Assistant Examiner

FIG. 1 is a side elevational view of an air box for bicycles showing my new design, the opposite side being a mirror image thereof;

FIG. 2 is a top plan view thereof;

FIG. 3 is a bottom view thereof;

FIG. 4 is a rear elevation view thereof; and

FIG. 5 is a front elevation view thereof.

I claim:

The ornamental design for an air box for bicycles, as shown.
